UNITED STATES PATENT OFFICE.

WILLIAM S. SKINNER, OF PHILADELPHIA, PENNSYLVANIA, ASSIGNOR TO
THE GERMANTOWN TOOL WORKS, OF SAME PLACE.

DESIGN FOR A HATCHET.

SPECIFICATION forming part of Design No. 15,567, dated November 18, 1884.

Application filed August 10, 1883. Term of patent 14 years.

To all whom it may concern:

Be it known that I, WILLIAM S. SKINNER, a citizen of the United States, residing at Philadelphia, in the county of Philadelphia and 5 State of Pennsylvania, have invented and produced a new and original Design for Hatchets, of which the following is a specification, reference being had to the accompanying drawings, forming part thereof, in which—

10 Figure 1 is a side elevation of my newly-designed hatchet. Fig. 2 is a section thereof in line *x x*.

Similar letters of reference indicate corresponding parts in the two figures.

15 The leading feature of my design is the head of a hatchet having a neck of reduced form.

In the drawings, A represents the blade, B the eye, and C the head. The head C consists of the neck *a* and poll *b*, said neck joining 20 the poll and eye and made concave, so that a portion of the same is reduced, or of less diameter than the poll. The neck is many-sided, and the poll is cylindrical, the places of junction of the sides of the neck and poll being

scalloped, as at *c*. The top and bottom of the 25 sides of the eye are swelled respectively upward and downward, as at *B'*, the curvatures of the swells being described from a common center, and the forward ends of the swells join the swells of the blade A, and the rear ends 30 thereof join the concave neck *a* of the head C, so that the top and bottom of the hatchet is convex-concavo from the blade to the poll *b*, making graceful curves at said places.

I claim—

35 The design for a hatchet consisting of the blade A, the eye B, and the head C, the latter having a concave and many-sided neck, *a*, and a cylindrical poll, *b*, with scallops *c*, said eye B being swelled at top and bottom, as at *B'*, 40 forming convexities which join the concavities of the neck, the curvatures of the swells being described from a common center, all as shown.

WM. S. SKINNER.
